UNITED STATES PATENT OFFICE.

CHARLES GIERATZ, OF MILWAUKEE, WISCONSIN, ASSIGNOR TO PROTECTIVE BOARD COMPANY, NOT INCORPORATED, A COPARTNERSHIP COMPOSED OF PAUL C. WEBER, M. J. FISCHBACH, WALTER FISCHBACH, ELMER FISCHBACH, AND CHARLES GIERATZ, ALL OF MILWAUKEE, WISCONSIN.

PUNCH-BOARD.

1,270,509.

Specification of Letters Patent. Patented June 25, 1918.

Application filed April 27, 1917. Serial No. 164,829.

To all whom it may concern:

Be it known that I, CHARLES GIERATZ, a citizen of the United States, and resident of Milwaukee, in the county of Milwaukee and State of Wisconsin, have invented certain new and useful Improvements in Punch-Boards; and I do hereby declare that the following is a full, clear, and exact description thereof.

This invention relates to new and useful improvements in game apparatus, particularly to that class of devices known as punch boards.

It is in general the object of the present invention to greatly improve the construction and efficiency of all devices of this character so as to prevent unscrupulous persons from improperly using same.

Devices of this character ordinarily are constructed from a board having a plurality of pockets, in each of which a colored pellet is disposed, the latter each indicating a certain value and being punched from the pockets by the persons using the board.

Ordinarily, unscrupulous persons could very readily carry one or more of the pellets of desired color with them and force the same through the pockets which have already been punched, and thereby obtain the prizes or the like, which are usually given to the operators of the board, without having punched any of the pellets from the board.

The object of the invention is carried out by providing a very simply constructed means for preventing any one from forcing a pellet through one of the pockets of the board from the outside face thereof.

With this general object in view, the invention resides in the novel features of construction, combination and arrangement of parts, which will be hereinafter more particularly described, claimed and shown in the drawing wherein:

Figure 1 is the plan view of the board constructed in accordance with my invention, parts of the same being broken away to more clearly illustrate the important features.

Fig. 2 is the transverse section taken on the plane of the line 2—2 of Fig. 1.

Referring more particularly to the figures 50 of the drawing, wherein similar reference characters indicate like parts, the numeral 1 designates broadly one of my improved punch boards mounted in any suitable form of frame 2. The outer surface of the board 55 is covered with a sheet of paper or other material which will tear easily, on which is printed a number of circles 4 which indicate the points to be punched.

Those portions of the paper covering 3 disposed within the circles 4 are directly above openings 5 formed through the plate 6 which is ordinarily and preferably formed of a wooden board. Two other boards or plates 7 and 8 are positioned beneath plate 6, and each has the same number of openings as are formed in the first mentioned plate 6. The openings 9 in the plate 8 are the same diameter as the openings 5, while the openings 10 in the plate 7 are of somewhat larger diameter. All of the adjacent openings in the several boards or plates are alined as shown in Fig. 2.

These three plates may be held together in any preferred manner, and the bottom surface of the lowermost plate 8 is covered by a sheet of heavy paper or the like 11 in the same manner that the outer surface of the upper plate 6 is covered. The covering 11 serves to hold indicating pellets 12 of various colors within the openings 9, one of the pellets being disposed in each opening.

Punch boards of ordinary construction are formed similarly to the device above described. In order to operate the same it is necessary to insert a suitable instrument of small diameter within any one of the openings, so as to force the indicating pellet therefrom. In carrying out this operation the paper covering 3 over the opening punched is punctured as shown at A, thereby notifying the next user of the board that in order to force an indicating pellet from its pocket or opening 9 it will be necessary

for him to puncture one of the unbroken circles 4. When the pellets have been forced from the openings 9 the covering 11 is necessarily broken as indicated at B in Fig. 2. 5 This permits a person to readily drop a pellet of any desired color through an opening which has already been punched, and as it rolls down to the bottom of the board, claim that he has punched one of the openings and 10 is entitled to the prize which the color of the pellet indicates. In this manner any one may very readily cheat and obtain a prize to which he is not entitled.

To defeat the designs of such unscrupulous persons my invention has been constructed, and in its preferred embodiment consists in disposing a disk 13 in each of the openings 10 in the plate 7. The diameter of these disks is substantially equal to 15 the diameter of said openings and therefore are larger than the openings 5 and 9 so that they are always in position to prevent any instrument or article from being inserted into the openings 9 and through the lower 20 ends thereof. An elongated projection or stud 14 is carried by one face of each of the disks 13, said studs engaging the pellets 12 as clearly shown in Fig. 2. Before any 25 of the circles 4 are punched, the disks 13 are disposed at the tops of the openings 10, and the studs 14 for the major portion of their length also positioned within said openings 10. When the instrument provided has been inserted through one of the 30 openings 5 and pressed inwardly until it engages the disk 13 in the adjacent opening 10, continued pressure of the instrument will force the pellet through the covering 11, whereupon the disk and its stud drops down 35 as shown in Fig. 2. If any one now endeavors to insert a pellet through an opening which has already been punched, it will lodge in the portion 10 thereof and not pass entirely through the board as was formerly 40 the case. Each of the studs 14 is of a diameter slightly smaller than the openings 9 and they are disposed substantially centrally of the disks 13 so that they may readily slide through and engage the pellets. 45 50 The simple provision of the headed studs very effectively overcomes a difficulty which has heretofore been experienced, and it is obvious that it will be impossible for any one to cheat a board constructed in accordance with the invention. All of the parts are of very simple construction and the total cost of a board of this type will only be slightly greater than that of the old type of board. 55 The headed studs may well be rivets of appropriate size. After all of the circles 4 have been punched the empty board may be returned to the manufacturers thereof and again filled with the pellets 12; thus it will

be seen that one board may be used a great many times. 65

Having thus described my invention what I claim as new is:

1. A device of the class described comprising a plate having a transverse opening formed therethrough, a covering for one end of the opening, an indicating device in the opening, and means for preventing the insertion of an article through said opening. 70

2. A device of the class described comprising a plate having a transverse opening formed therethrough, a covering for one end of the opening, an indicating device in the opening, and a member disposed across said opening to prevent the insertion of an article therethrough. 75

80 3. A device of the class described, comprising a plate having an opening formed therethrough, the intermediate portion of the opening being enlarged, a covering for one end of the opening, an indicating device 85 in the opening, and a disk disposed in said enlarged portion and extending across the opening to prevent the insertion of an article therethrough.

4. The combination with a plate having a 90 transverse opening formed therethrough, and an indicating device in said opening, of means for forcing said device from the opening, and a member connected with said means to prevent the insertion of an article 95 through said opening.

5. The combination with a plate having a transverse opening formed therethrough, and an indicating device in said opening, of a member disposed across said opening to 100 prevent the insertion of an article therethrough, and an elongated projection carried by the member to force the indicating device from said opening.

6. The combination with a plate having a 105 transverse opening formed therethrough, and an indicating device in said opening, of a disk movable longitudinally of said opening and adapted to prevent the insertion of an article therethrough, and a stud secured 110 to one side of said disk centrally thereof to engage and force said indicating device from said opening.

7. The combination with a plate having a transverse opening formed therethrough, the intermediate portion of the opening being enlarged, and an indicating device in said opening, of a disk movable longitudinally in said enlarged portion, said disk being of larger diameter than the ends of the opening and adapted to prevent the insertion of an article therethrough, and a stud secured to one side of said disk centrally thereof to engage and force the indicating device from the opening. 115 120 125

8. In a device of the class described, a

punch board comprising a pair of plates having alined openings therein, an additional plate disposed between the pair of plates and having an opening of larger 5 diameter than the first mentioned openings and alined therewith, a covering over the outer end of the opening in one of said pair of plates, an indicating member in the last mentioned openings, a disk in the opening

in the additional plate, and a stud carried 10 by the disk and engageable with the indicating member to force the same through said covering and out of its opening.

In testimony that I claim the foregoing I have hereunto set my hand at Milwaukee, 15 in the county of Milwaukee and State of Wisconsin.

CHARLES GIERATZ.
